UNITED STATES PATENT OFFICE.

LLOYD E. BURHANS, OF YONKERS, NEW YORK.

CLOSURE CONSTRUCTION.

Application filed February 14, 1924. Serial No. 692,741.

To all whom it may concern:

Be it known that I, LLOYD E. BURHANS, a citizen of the United States, residing at Yonkers, in the county of Westchester and State of New York, have invented certain new and useful Improvements in Closure Construction, of which the following is a full, clear, and exact description, such as will enable others skilled in the art to which it appertains to make and use the same.

This invention relates to a closure and has particular reference to such a device as is usually employed in strong rooms, vaults and safes, although it is to be understood that the subject matter of the present invention might be used to advantage to certain other associations.

It is an object of the invention to provide an improved closure construction by means of which the entrance of foreign matter into a safe or other receptacle may be prevented to a maximum extent so that, in the event of fire the contents will be safeguarded against the action of smoke and water aside from the fact that an unauthorized person endeavoring to secure entrance to the receptacle will be virtually unable to do so for the reason that it will be extremely difficult to effectively use a tool or explosive on the closure.

It is a further object of this invention to provide a construction of the character specified by means of which the closure will be locked in a manner additional to the manner in which this has been heretofore deemed practicable so as to furnish a further safeguard against successful attempts to open the same.

An additional object is that of providing a closure which will efficiently perform the purposes for which it is intended and which will also be economically and readily manufactured and assembled.

Other objects of the invention will be in part obvious and will in part appear hereinafter.

The invention accordingly comprises the features of construction, combinations of elements, and arrangement of parts, which will be exemplified in the construction hereinafter set forth and the scope of the application of which will be indicated in the claims.

For a fuller understanding of the nature

and objects of the invention reference should be had to the following detailed description taken in connection with the accompanying drawing, in which:

Figure 1 is a front elevation of a safe and showing certain portions of one of the closure panels thereof broken away to disclose the underlying construction,

Fig. 2 is a fragmentary sectional side view taken along the lines 2—2 in the direction of the arrows indicated in Fig. 1,

Fig. 3 is a similar view of a portion of the closure operating mechanism,

Fig. 4 is a fragmentary sectional plan view of the safe mechanism as illustrated in Fig. 1 and taken along the lines 4—4 thereof, this view showing the parts in one position,

Fig. 5 is a view showing one form of certain mechanical parts as illustrated in Fig. 4, the parts in this view however, being in a position different from that shown in the preceding figure,

Figs. 6 and 7 are sectional views taken along the lines 6—6 and 7—7 and in the direction of the arrows indicated in Figs. 4 and 5, respectively, and

Fig. 8 is a fragmentary view of an alternative form of mechanism which may be employed to advantage in certain instances.

The illustrated embodiments show a safe construction to which the invention is particularly applicable. Thus, it will be seen reference being had to Fig. 1, that the numeral 10 indicates the body of the safe which may be of any desirable type and which in the present exemplification has an open front; the top, bottom and side walls of the structure constituting the jam portions 11 against which the closure seats.

This closure may include a pair of panels 12 and 13 which are swingingly supported by the use of hinges 14, so that the panels are movable away from and towards the jamb. These panels have been shown as of exaggerated size in order to assure a clear illustration of the locking mechanism hereinafter described and as will be seen, reference being had to Fig. 4, the opposed side edges of the panels may be stepped as indicated at 15, it being understood that this construction may be modified in many particulars in order to assure a most efficient sealing and a ready opening of the closure

without the panels interfering with one another in their swinging movements.

A pair of bars or bolts 16 is slidably mounted upon the rear face of each panel 5 and when projected the outer ends of these bars will extend beyond the edges of the panel and into sockets 19 formed in the jamb 11. In order to effect this projection and also to enable the bars to be retracted 10 any suitable mechanism may be utilized. For example: a pinion 18 may be employed for each pair of bars and be mounted between and engage rack portions 17 formed adjacent the inner ends of the same. A 15 knob 20 may be connected with the pinion and lie at a point beyond the outer face of the panel. Thus, when each knob is turned in one direction the ends of certain of the bars 16 will be projected to occupy a position, one within each of the sockets 19, while a turning of the knob in an opposite direction will result in a retraction of the bars from within the sockets.

Extending from those edges of each of 25 the panels which are adjacent the hinges 14, are one or more locking elements. These, in the present instance, each include a flattened head 21, which extends beyond the inner edge of the panel and when the latter is in 30 closed position projects into a socket which as in Figs. 6 and 7, may have a mouth portion in the nature of a keyhole slot 22 of a size sufficient to permit the passage of the head 21, the body of this socket, to the rear 35 of the slot 22, being divided into two opposed arcuate chambers 23.

It is thus obvious that with the locking elements in the position shown in Fig. 4, 40 the panels 12 and 13 may be freely swung and in each instance upon these panels being moved to a position in which they will be seated against the jamb, the elements aforementioned, will enter the keyhole slots or openings 22 provided for this purpose, 45 while upon the closure being opened the heads will be free to swing through the slots 22 and clear of the jamb. If now, after each of these heads has been brought to a position at which it extends into the socket 50 and to the rear of the jamb face and is turned, in the present instance, through an arc of 90°, the wings of the head will be moved from the position shown in Fig. 6 to that indicated in Fig. 7 and in this latter 55 position it will be understood that the panels cannot be swung relative to the safe body due to the fact that the locking elements will prevent this operation from being effected, it being understood that in order to 60 swing the panels to their open position, each of the heads will again have to be turned to a point at which its wings are in line with the slot 22, as in Fig. 6, so as to freely swing through the same and beyond 65 the jamb.

Now with a view of moving the locking elements in the manner indicated, it will be noted that each of the same is carried by a shaft 24 rotatably mounted upon the rear face of the panel and each of these shafts in the present instance, is formed with an annular series of teeth 25 in engagement with corresponding teeth 26 providing rack portions forming a part of the bars 16.

Thus, it is to be understood that with the bars in their retracted positions the panels constituting the closure are free to be swung into either open or closed positions. During such swinging the locking elements, provided in the present instance by the heads 21, will also be free to enter or withdraw from the jamb sockets into which they are capable of being extended. If now, upon the panels being in closed position the knobs 20 carried thereby are rotated, this will result, first, in the bars 16 being projected so that the outer ends of the same come to extend into the sockets 19 provided for their accommodation; secondly, as a consequence of this projection of the bars, the shafts 24 will be rotated thus causing the heads 21 carried thereby to be moved from the position shown in Figs. 4 and 6, to the position shown in Figs. 5 and 7, it being noted that the parts are so correlated in the present instance, that a full projection of the bar 16 will cause a sufficient rotation on the part of the shafts 24 to swing the wings of the heads 21 into a position at which they will bear against the remote side faces of the chambers 23, i. e., those faces of the same which are opposed to the faces in line with the slot 22.

In the present instance, the shafts 24 carried by the panel 13 are each formed with a bore, the outer end of which is constricted and provides screw threads 27. Mounted for movement one within the bores of each of these shafts are rods 28 having a screw threaded portion 29 engageable with the screw threads 27 and being further formed with a head 30 adapted to bear against the shoulder provided at the inner end of the reduced bore portion of the shaft. It is here to be noted that the distance between the innermost screw thread 29 and the inner face of the head 30 is greater than the length of the constricted bore portion within which the screw threads 27 are formed and as a consequence it will be obvious that if the rods are rotated to a sufficient extent in one direction they will each move relative to the shaft carrying them until the final convolution of the thread 29 will move beyond the outermost convolution of the thread 27 as in Fig. 5 and if the movements of the rod and shaft in opposite directions relative to each other are continued, the head 30 of the former will come into contact with the shoulder provided by

the constricted bore portion of the latter, the purpose of this construction being hereinafter brought out.

The shafts 24 associated with the panel 12 are arranged to lie in line with the shafts carried by the panel 13 when the closure is seated against the jamb and the shafts 24 carried by the panel 12 are furthermore each formed adjacent their ends with screw 5 threaded bores the threads of which correspond in pitch to the threads 27 and 29. Thus, due to the fact that the adjacent edges of the panels 12 and 13 are formed with 10 openings in line with the shafts 24, it will be obvious that upon the rods 28 being turned relative to the shafts carrying the same, and as a consequence being fed outwardly, that the outer end of each rod will move through the openings in the edges of 15 the panels and enter the bore of the shaft 24 associated with the panel 12. The outer end of each rod is provided with a screw thread 32 corresponding in pitch to that of the screws 27, 29 and 31 and thus upon 20 entering the bore of the shaft in the manner aforementioned, the screw threads 32 and 31 will interengage and as a consequence the rod 28 will be fed, not alone by the movement of the threads 27 and 29 relative 25 to each other, but also by the corresponding relative movement of the threads 31 and 32.

From the foregoing it will be appreciated that the threads 31 and 32 will be in 30 engagement upon the last convolution of the thread 29 being disengaged from the corresponding convolution of the thread 27 and as a consequence the continued rotation of the rod 28 will result in the head 30 being 35 brought into intimate contact with the already mentioned shoulder in the shaft 24 of the panel 13. Thus, continued movement of the rod relative to the shafts will cause the ends of the same to tend to move towards each other, but due to the fact that these ends are actually in the form of locking elements, provided by the heads 21, the inner edges of these heads will be caused 40 to intimately bear against the inner faces of the plates 33 which cover the sockets into which the locking elements extend, so that, if this movement of the rod is continued to a sufficient extent the parts of the safe 45 walls which provided the jamb portion 11 will actually be constricted, resulting in the adjacent faces of the jamb and closure being pressed intimately into contact with each other and as a consequence also pressing the adjacent faces of the panels 12 and 13 into contact. This action will further cause a reduction in the joint space 50 between the various elements providing the closure and due to the frictional contact which will necessarily exist between the heads 21 and the plates 33, it will be an

extremely difficult matter to turn the shafts 24 until the tension exerted upon the parts is released.

Now with a view of turning the rods in the manner before brought out, any desirable mechanism may be utilized, for example, referring to Fig. 2, the panel 13 may carry a hand wheel 34 mounted upon a shaft which extends through and to the rear of this panel at which point it mounts 70 a gear 35 engageable with corresponding gears 36 secured to each of shafts 37. These shaft at points adjacent the shafts 24 are formed with worm portions 38 in engagement with the teeth of worm wheels 39, 75 the latter being slidably keyed upon the rods 28 as has been indicated at 40. As a result, due to the fact that the keyway in each rod 28 is of sufficient length to allow the full projection and retraction of the rod and furthermore for the reason that the movements of the worm wheels 39 are in the present instance, limited, it will be seen that by the turning of the shafts 37 the desired 80 projection of the rods 28 is achieved. As 85 a consequence the resultant operations aforementioned are accomplished.

In certain instances it may be found due to wear of the parts or for other reasons, that as the rod 28 moves toward one of the 90 shafts 24 the screw threads on the former do not engage with the screw threads in the bore of the latter. In other words, the forward ends of the threads may fail to properly engage. In order to overcome any difficulties in this connection, a structure such as has been shown in Fig. 8 may be utilized.

In this view it will be noted that the outer and screw threaded end portion of one of the rods 28 has been shown together with 100 one of the shafts associated with the panel 12. This shaft has been indicated by the numeral 41 and it will be seen that contrary to the structure depicted in the preceding figures, this shaft terminates at a point relatively remote from the outer edge of the panel 13. Carried at the end of the shaft 41 is a collar 42 which is rigidly affixed thereto and has a bore providing a keyway 43 within which bore the head 44 of a rod 45 is capable of moving, it being observed that the head carries a key 46 slideable within the groove or keyway 43, so that the movements of the rod 45 are limited to a direction coextensive with the axis of the shaft 41. Fixedly attached to the rod 45 is a sleeve 47 formed with internal screw threads corresponding to the pitch and diameter of the threads 32, and it will finally be observed that a spring 48 is, in the present instance, interposed between the outer end of the collar 42 and the inner face of the sleeve 47 so that these parts are normally maintained in the position shown.

Assuming, for example, that as the rod 130

28 is advanced toward the sleeve 47, the screw threads of the latter are not in a position at which they will immediately engage with the screw threads of the former, it will be appreciated that a continued projection of the rod 28 will result in the sleeve and rod 45 carrying the same being moved towards the shaft 41, this movement being permitted by virtue of the construction before described.

According to the mechanism employed in the present instance, the rod 28, in causing a movement on the part of the sleeve relative to the shaft, will usually make less than a complete revolution, in that at some point in its path of rotation the screw threads will begin to interengage. This engagement will be continued until the parts are subjected to tension, and, upon the initiation of this tension, the sleeve will again move to its normal position, i. e., that shown in Fig. 8 so that, by means of the construction shown the difficulties aforementioned, will be avoided.

Briefly reviewing, the functions derived by the use of the mechanism illustrated, and the manner in which they are achieved it will be understood, assuming the parts to be in the position shown in Fig. 1, that a turning of the knob 20 associated with each of the panels will cause the bars 16 to be retracted from positions within the sockets 19. Coincident with this retraction, the shafts 24 will be turned so that the wall or jamb engaging members, i. e., the heads 21, will be moved from positions at which they are anchored to positions in which upon the door panels being swung they may freely pass through the slots 22, formed in the plates 33. The closure may now be opened by swinging the same on the hinges 14 provided for this purpose.

Conversely, after the parts are opened and it is desired to completely lock the closure against movement, as well as to prevent a movement of the mechanism which affects this locking, the panels may initially be swung shut. Upon the knobs 20 being now turned, the bars operated thereby will be projected once more to the positions shown in Fig. 1, which will also result in the wall engaging means being turned to positions at which they may not be withdrawn from the sockets into which they now extend, (it being appreciated that during the closing of the panels the heads have again passed through the slots 22).

The elements 21 will now be found to occupy positions such as have been shown in Figs. 5 and 7, i. e., in which the arms or wings of these elements are not in alignment with the slots 22, but are, in the present instance, in engagement with the proper faces of the chambers 23. The operator will now rotate the shaft 37 and this rota-

tion will result in the rods 28 being fed from the position shown in Fig. 4 to the position shown in Fig. 5, during which feeding it will be appreciated that the outer ends of the rods will enter into and have 70 their screw threads 32 engage with the screw threads 31 of the bores formed in the shafts 24 carried by the panel 12. In moving to such position, it will be understood that the mechanism will cause a tension to be placed 75 on the parts. In other words the walls adjacent the jamb portions of the receptacle will tend to move towards each other to close to a maximum extent all joints, or in other words to bring adjacent surfaces of the 80 panels and jams into most intimate contact. This, as before brought out, will also result in the shafts 24 being virtually locked against rotation in that it will be necessary to relieve this tension before they can be 85 again turned.

It will be obviously understood that any desirable lock mechanism might be utilized, such as, for example, that indicated by the reference numeral 49 to prevent any turning of either the knobs 20 or the shaft 37 when the parts are in closed position, it being seen, referring particularly to the mechanism which drives the gears 36, that the gear 35 may be retracted to a position in 90 which it will not mesh with the first named gears, and in fact be prevented from moving into meshing position by interposing a bar 50 between these elements, this bar being 95 operated by the locking mechanism before mentioned. In conclusion, attention is invited to the fact that the construction of the individual mechanical parts might be varied in numerous particulars to assure a ready working of the same and also to expedite the steps involved in the manufacture and assemblage of the mechanisms. 100

Furthermore, it will be appreciated in certain instances where for example, the invention is employed in connection with vault construction, that the tensioning of the parts will not result in any appreciable movement of the jamb portions towards each other, due to the rigid construction of the wall. However, due to the tensioning 110 effect achieved, it will be understood that a closure lock construction will be provided, which will be extremely efficient. 115

It will be understood from the foregoing that among others, those objects specifically aforementioned have been accomplished, and since certain changes may be made in the above construction and different embodiments of the invention could be made without departing from the scope thereof, it is intended that all matter contained in the above description or shown in the accompanying drawing shall be interpreted as 120 illustrative and not in a limiting sense. 125

It is also to be understood that the follow- 130

ing claims are intended to cover all of the generic and specific features of the invention herein described, and all statements of the scope of the invention, which, as a matter of language, might be said to fall therebetween.

Having described my invention what I claim as new and desire to secure by Letters Patent, is:

- 10 1. A device of the character described, including in combination, a receptacle provided with an opening, a closure for said opening, said closure including a plurality of panels and means carried by said closure and adapted to press the adjacent surfaces of said panels into contact with each other and further adapted to press adjacent surfaces of said closure and receptacle into intimate contact whereby to reduce the size 15 of the joints existing between said elements.
2. A device of the character described, including in combination, a receptacle formed with an opening, a closure therefor, said closure including a plurality of panels, locking heads carried by each of said panels and being adapted to extend into sockets formed in the receptacle walls upon said closure being moved to closed position, means for locking said heads within said sockets, 30 means for connecting heads associated with different panels to each other, and means exerting a draft upon said heads whereby to tend to move the same towards each other and to bring adjacent surfaces of the panels 35 and receptacle walls into intimate contact.
3. A device of the character described, including in combination, a receptacle formed with an opening, a closure therefor, bolts carried by said closure and projectable into sockets formed in the receptacle, locking elements also carried by said closure and projectable into sockets formed in said receptacle, means for locking said elements within said sockets, and means for exerting 40 a draft upon said elements whereby to tend to move adjacent surfaces of said panels and receptacles into intimate contact with each other.
4. A device of the character described, 45 including in combination, a receptacle formed with an opening, a closure therefor, said receptacle being formed with sockets, bars carried by said closure, locking heads adjacent the outer ends of said bars and adapted to be extended into said sockets, means carried by one of said bars and movable into contact with another for connecting the same, and means for moving said bars and locking heads towards each other 50 whereby to tend to move adjacent surfaces of said receptacle and closure into intimate contact.
5. A device of the character described, 55 including, in combination, a receptacle presenting an opening, a plurality of panels
- adapted to be positioned within the opening to close the same, a shaft carried by one of the panels and having the threaded bore formed in one of its ends, means on the other end of said shaft to lockingly engage 70 the receptacle on one side of said opening, a shaft carried by another of said panels in alignment with the first shaft, means on the second shaft to lockingly engage the receptacle on the opposite side of said opening, a 75 rod adapted to be aligned with said shafts and having formed on one end thereof threads adapted to cooperate with the threads of said bore to permit the rod to be screwed therein, and cooperating means on 80 said rod and the second shaft adapted to limit the relative movement of the latter shaft and the rod as the rod is screwed into said bore.
6. A device of the character described, 85 including, in combination, a receptacle presenting an opening, a plurality of panels adapted to be positioned within the opening to close the same, a member adapted to lockingly engage the receptacle carried by 90 each of said panels, one of said members having a threaded bore formed therein, a rod having on one of its ends a threaded portion adapted to be screwed into said bore, means to screw the rod into the bore, 95 and means to limit the relative movement of the rod and another of said members when the rod is screwed into said bore.
7. A device of the character described, 100 including, in combination, a receptacle presenting an opening, a plurality of panels adapted to be positioned within the opening to close the same, a member adapted to lockingly engage the receptacle carried by 105 each of said panels, one of said members having a threaded bore formed therein, a rod having on one of its ends a threaded portion adapted to be screwed into said bore, means to rotate said rod, means to cause the threaded portion of the rod to 110 enter said bore upon rotation of the rod, and means to limit the relative movement of the rod and another of said members when the rod is screwed into said bore.
8. A device of the character described, 115 including, in combination, a receptacle presenting an opening, a plurality of panels adapted to be positioned within the opening to close the same, a shaft carried by one of the panels and having the threaded bore 120 formed in one of its ends, means on the other end of said shaft to lockingly engage the receptacle on one side of said opening, a shaft carried by another of said panels in alignment with the first-named shaft, means 125 on the second shaft to lockingly engage the receptacle on the opposite side of said opening, a rod extending in a direction parallel to said shaft and having a threaded connection with said second shaft and 130

a threaded end adapted to enter said bore upon the rotation of the rod in said connection in one direction, and cooperating means on said rod and the last-mentioned shaft to limit the relative movement thereof.

9. A device of the character described, including, in combination, a receptacle presenting an opening, a plurality of members adapted to be disposed within said opening to provide a closure therefor, a member carried by each of said panels and adapted to lockingly engage the receptacle, a projection extensibly mounted on one of said members, said projection and another of said members having co-axial threaded bores formed therein, a rod having the threaded portion adapted to cooperate with the threaded bore on said other member and a threaded end adapted to be screwed into said threaded bore and yieldable means to maintain said projection extended toward said rod.

10. A device of the character described, including, in combination, a receptacle pre-

senting an opening, a plurality of members adapted to be disposed within said opening to provide a closure therefor, a member carried by each of said panels and adapted to lockingly engage the receptacle, a projection extensibly mounted on one of said members, said projection and another of said members having co-axial threaded bores formed therein, a rod having the threaded portion adapted to cooperate with the threaded bore on said other member and a threaded end adapted to be screwed into said threaded bore, yieldable means to maintain said projection extended toward said rod and cooperating means on the rod and said other member to limit the relative movement thereof after the threaded end of the rod has entered the threaded bore of the projection and the threaded portion on the rod has been screwed through the threaded bore of said other member.

In testimony whereof I affix my signature.

LLOYD E. BURHANS.
